(57) **CLAIM**

The ornamental design for a steering wheel for vehicle as shown and described.

DESCRIPTION

FIG. 1 is a front perspective view of a steering wheel for vehicle showing our new design in a first state in which a central portion of the steering wheel for vehicle is in a first position;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view thereof in a second state in which the central portion of the steering wheel for vehicle is rotated to a second position;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front perspective view thereof in a third state in which a screen unit on the rotated central portion of the steering wheel for vehicle protrudes in the form of a keypad;

FIG. 16 is a front view thereof;

FIG. 17 is a rear view thereof;

FIG. 18 is a left side view thereof;

FIG. 19 is a right side view thereof;

FIG. 20 is a top plan view thereof; and,

FIG. 21 is a bottom plan view thereof.

(Continued)

The broken lines depict portions of the steering wheel for vehicle that form no part of the claimed design. The present design is a dynamic design and can be deformed from a first state to a second state in which the central portion of the steering wheel is rotated and to a third state in which the rotated central portion of the steering wheel protrudes in the form of a keypad.
